MATCH BOOK HOLDER

Cornelius J. Donovan, Yonkers, N. Y.

Application August 31, 1943, Serial No. 500,615

6 Claims. (Cl. 206—48)

This invention relates to a device for attaching a match book to a package of cigarettes, whereby a smoker will conveniently maintain both cigarettes and matches together as a unit, with numerous advantages following from such an arrangement.

One of the inconveniences most often encountered by the cigarette smoker is the mislaying or loss of his match book due to a lack of attachment or direct connection of the matches with the cigarettes. The smoker often carries a package of cigarettes in one pocket, and a book of matches in another. To light a cigarette, he first withdraws the package of cigarettes from his pocket, extracts a cigarette from the package, places it between his lips and then restores the package of cigarettes to his pocket. He next starts a search, and often in vain, through his remaining pockets in an effort to locate a book of matches. Having found it, he takes it from his pocket, lights the cigarette and then restores the match book to his pocket. In many instances, the smoker will carelessly toss the match book on a table before him and later walk off without it so that a subsequent effort to light a cigarette will result in the discovery that he is without matches. While match books are so carelessly handled and often mislaid, presumably because they are often obtained without cost to the smoker, the cigarettes are more carefully preserved, so that it is apparent that an arrangement whereby the cigarettes and the matches may be unitarily carried, is of value to the smoker.

The primary object, therefore, of the present invention is to provide a relatively simple and compact device by means of which a match book may be securely but detachably affixed to the conventional type of cigarette package whereby the matches will always be at hand when it is desired to smoke, and, in addition, the operations of lighting the cigarette and restoring the cigarettes and matches to the pocket will be greatly simplified.

I am aware that prior to this invention, efforts have been made to provide means by which a match book could be attached to a cigarette package, but devices of the prior art have been unsatisfactory for the reasons that the same were bulky, were difficult to attach to the cigarette package, did not engage the cigarette package effectively, and particularly when the package was partly empty, and possessed many other deficiencies preventing them from satisfying the needs of the public.

The present invention contemplates the provision of a spring clip which resiliently engages the package wrapper or covering so that it may be instantly placed in position on the cigarette package, and which is provided with a match-book-engaging loop to hold the match book flatwise, yet shiftably, against the face of the cigarette package in a manner hereafter described.

10 In the accompanying drawing, in which an illustrative embodiment of the invention is disclosed:

Fig. 1 is a front view of a package of cigarettes, with the improved match book holder attached thereto;

Fig. 2 is a similar view showing the match book in place with a part of the covering of the match book broken away;

Fig. 3 is a plan view of a match package, 20 with the match book holder in position and a portion of the wrapper of the cigarette package torn away;

Fig. 4 is a vertical sectional view through a portion of the cigarette package showing the 25 match book holder in place and holding an open book of matches;

Fig. 5 is a perspective view of the match book holder; and

Fig. 6 is a view of a part of the back of the 30 holder, showing the tongue thereon.

The improved match book holder may be made of various materials, such as sheet metal, plastic, or the like, and it may be made in various shapes and forms to suit various requirements 35 and to meet differences in the shape and style of cigarette packages. In the drawing, an illustrative form of the holder is shown as applied to the conventional paper-wrapped cigarette package, but it will be understood that the holder 40 may be varied in many respects to permit it to be used on all the types of cigarette packages now in use or which may be used in the future.

With reference to the drawing, 1 indicates a 45 conventional type of cigarette package containing a number of cigarettes 11 which are wrapped in an outer wrapping 9 of paper, within which is contained a lining 10. The improved match book holder adapted to be detachably secured to the package 1 is preferably, but not necessarily, stamped or moulded in one piece, and is provided with a flat base portion 2 which, when the device is attached to the cigarette package, is disposed flatwise against a face of 55 the package, as clearly shown in Figs. 1 and 2.

The base portion 2 may be slotted at 6 for lightness. The device, in the form disclosed, is substantially T-shaped, and at one end is provided with the integrally-formed bar or member 3 formed with a longitudinally-extending slot 4, so that said member 3 is in effect a loop which embraces the covering 13 of the match book 12, as hereafter described. At its opposite end, the base portion 2 is turned over as indicated at 7 to provide a downwardly-extending tongue 8 which is adapted, when the device is attached to a cigarette package, to be inserted into the package between the cigarettes 11 and the paper covering or wrapping of the package, as shown in Fig. 4.

The device is thus in the nature of a clip which is attached to the cigarette package by being clipped over the wrapping of the same, and since the tongue 8 is resiliently urged toward the back face of the base portion 2, the wrapper inserted between the back face of the base 2 and the tongue 8 will be firmly gripped between these parts and the device thus securely, yet detachably, affixed to the cigarette package.

The loop member 3, which is disposed transversely of the package, as shown in Fig. 1, extends slightly angularly forwardly from the base portion 2, it being bent to this slight angularity as at 5. This permits easy insertion of the covering 13 of the match book through the slot 4, which will, because of the slight angular disposition of the loop member 3, frictionally engage the surface of the match book covering and resist too-free sliding movement of the covering through the slot 4.

From the foregoing, the operation of the device will be readily understood. When a new package of cigarettes is purchased and it is desired to attach the match book holder to it, a small slit or opening is provided in the top of the wrapper of the package with the finger nail, and the end of the tongue 8 is inserted in the small slit-opening thus made. It will be observed that the end 15 of the tongue 8 is tapered so that only a small opening need be made in the wrapper which will be enlarged by the tongue as shown at 14, as the tongue 8 is thrust inside of the package between the cigarettes and the paper wrapping. The tongue 8 is made very thin and smooth to facilitate the easy insertion of it without damaging the cigarettes. If desired, the tongue can be inserted between the outer wrapper 9 and the lining paper 10 to be thereby kept out of contact with the cigarettes.

With the device clipped to the cigarette package in the manner described, a match book is inserted in the holder by having its covering thrust upwardly through the slot 4 to the position shown in Fig. 2, the cover being frictionally held by the slot. It will be noted that the slot is slightly longer than the width of the match book covering to enable the match book to be shifted angularly, as indicated in dotted lines in Fig. 2. This flexibility of attachment of the match book enables the user to shift or swing the match book with relation to the cigarette package to a position most convenient to him, thus enabling him to extract a match from the book and strike a light, yet maintaining the match book at all times attached to the cigarette package.

Since the device is attached to the covering or wrapping of the package, it will remain securely attached to the package regardless of the number of cigarettes remaining in the package. In other words, the removal of cigarettes from

the package and the resultant flattening of the package because of the decrease in its contents will have no effect upon the security of attachment of the device to the package.

With the match book attached to the cigarette package in the manner shown, the matches and the cigarettes are always held together, so that convenience in smoking will result.

While I have shown an illustrative embodiment of the invention, it is obvious that the same may be greatly modified without departing from the spirit of the invention. Since the device is made from a single piece of material, it can be made inexpensively, if desired, or it may be made 15 as an article of jewelry by making it of precious metal and embellishing or decorating it in many interesting ways.

What I claim is:

1. A match book holder for cigarette packages comprising, a doubled-over tongue portion having a front part and a rear part, the rear part constituting a single prong entrant into the cigarette package from one end of the package to clip the covering of the package between it and the front part, the front part overlying a face of the cigarette package and provided at its lower end with a forwardly-tilted integral cross bar of considerably less width than the width of the tongue, said cross bar being provided with a slot extending transversely of the cigarette package to which the holder is attached, said slot receiving and completely surrounding the back portion of the match book covering, said slot loosely receiving the covering of the match book whereby the match book may be angularly shifted by the fingers while remaining in the slot, to facilitate convenient striking of a match while the match book remains attached to the cigarette package.
2. A match book holder for cigarette packages comprising, a doubled-over tongue portion constituting a single-prong clip for engagement with the covering of a cigarette package, one end of said tongue being provided with a slender, forwardly-tilted cross-piece having a slot through which the back portion of the match book covering extends to hold the match book attached to the face of the cigarette package.

3. A match book holder for cigarette packages comprising, a doubled-over tongue portion constituting a single-prong clip for engagement with the covering of a cigarette package, one end of said tongue being provided with a slender, forwardly-tilted cross-piece having a slot through which the back portion of the match book covering extends to hold the match book attached to the face of the cigarette package, said slot loosely receiving the match book covering to thereby permit angular shifting of the match book within the slot while striking a match.

4. A match book holder for cigarette packages comprising, a doubled-over tongue portion constituting a single-prong clip for engagement with the covering of a cigarette package, one end of said tongue being provided with a slender cross-piece, the cross-piece being integral with the tongue and being of less width than the tongue and being provided with a narrow slot loosely receiving the match book cover and through which a part of the match book cover is extended to maintain the match book against the face of the cigarette package.
5. A match book holder for cigarette packages, as provided for in claim 4, and in which the

- 75

cross-piece is slightly tilted in respect to the tongue to cause the slot to frictionally engage the match book covering and resist too-free sliding movement of the match book through the slot.

6. A match book holder having a head at one end formed with a longitudinally-extending slot through which the covering of a match book extends to thereby hold the book against the face of a cigarette package, said holder having a 10 spring clip at its opposite end, said clip including

a single tongue entrant into the package between the covering of the package and the cigarettes therein, the slot through which the covering of the match book extends loosely receiving said covering whereby the match book may be angularly shifted within the slot by the fingers of the user to permit convenience in striking a match while the match book remains attached to the cigarette package.

CORNELIUS J. DONOVAN.
